BATH TUB STOOLS

Donald Montgomery, 5 Payne St., West Kildonan,
Winnipeg 17, Manitoba, Canada
Filed Dec. 3, 1962, Ser. No. 243,192
3 Claims. (Cl. 4—185)

The invention relates to a safety stool for insertion in a conventional bath tub and which permits the bather to sit comfortably on the inserted stool when taking either a spray bath or what is commonly called a sitz bath and without fear of accident through slippage of the stool in any direction within the tub.

A more detailed object is to provide a stool for insertion in the tub and which uses the applied weight of one seated on the stool to forcibly extend spaced, compressible lower members simultaneously into frictional contact with the side walls of the tub, said contact members being positioned and compressed with sufficient intensity to prevent slippage of the stool under the applied weight of the sitter and in any direction.

A further object is to provide a stool for insertion in the tub and which embodies upper, spaced seat sections, each supported by a pair of spread, crossed legs pivotally connected together in transverse alignment at their points of crossing one another and wherein the lower portions of all legs, below the pivot points, are extended outwardly and all provided with similar, compressible cups to simultaneously engage the side walls of the tub upon the weight of an individual being imposed on the seat sections and with sufficient intensity to prevent slippage of the cups in all directions.

A further object is to provide a simply constructed bath tub stool formed from relatively few parts which can be readily produced and fabricated from common stock material and easily and quickly assembled and which also can be quickly extended for use or collapsed for storage purposes.

With the above more important objects in view and other minor objects which will become apparent as the description proceeds, the invention consists in the arrangement and construction of parts hereinafter described reference being had to the accompanying drawings in which:

FIG. 1 is a plan view of the stool and as it appears in an extended position.

FIG. 2 is a face view of the stool as it appears in operative position within a standard bath tub and showing the lower portion of a shower protecting curtain extending downwardly within the tub.

FIG. 3 is an end view of the stool as it appears in FIG. 1.

FIG. 4 is an enlarged, side view of a waterproof cushion which can be detachably secured to the upper part of the stool when desired and resting on the seat sections.

FIG. 5 is an invert plan view of a broken away portion of the cushion and showing the spring bar which appears in FIG. 4 as passing centrally across the underside of the cushion and secured thereto by straps as appearing also, in FIG. 4.

FIG. 6 is an enlarged, vertical sectional view passing longitudinally through one of the cups and showing the end of one of the horizontal tubes entered frictionally therein.

In the drawings like characters of reference indicate corresponding parts, in the several figures.

The stool presents an outer set of legs A and B and an inner set of legs C and D which cross one another and which are pivotally connected together at their points of intersection by transversely aligned pivot pins E and F, and the connected legs A and D are set well apart

2

from those C and B for a reason which will become apparent as the description proceeds.

The upper ends of all legs terminate in similar, outwardly, horizontally disposed portions H and I and to 5 which spaced, seat sections J and K are securely attached.

I now mention that the pairs of legs, as a whole, and as shown in the drawings have been made from selected lengths of stiff metallic tubing and which have been interconnected by suitable elbows G. The various tubes 10 utilized in the forming of the outer and inner pairs of legs are herein specifically indicated by applied reference numbers.

The outer legs present lower outgoing tubes 1 and 2 connected by appropriate elbows to upgoing, slanting tubes 3 and 4 and in the same vertical planes as those 15 1 and 2. The upper ends of the tubes 3 and 4 are connected by elbows G to upgoing and inwardly slanting tubes 5 and 6, it being here noticed that the upper ends of the latter tubes are well above the pivot points E and 20 F. In a similar manner the inner pairs of legs C and D which cross those indicated as A and B present corresponding tubes 7, 8 and 9. It is necessary that the upper ends of the leg tubes 5 and 6 and those 9 support the spaced seat sections J and K which are of the kidney 25 shape shown, and such is brought about by utilizing elbows G to connect the tubes 5, 6 and 9 to pairs of horizontally disposed tubes 10 and 11, 12 and 13 extending outwardly and connected through elbows by intervening tubes 14 and 15. According to the above it will 30 be apparent that each pair of legs is a unit in itself, the two units being pivotally connected to one another by the pivots E and F, and each unit being held together by the seat sections which are fixedly secured to the tubes 10, 11 and those 12, 13.

35 The lowermost tubes of the stool are supplied at their outer ends with similar, compressible, friction cups L applied frictionally on the outer ends of the tubes. In order to prevent undue damaging of the interior of the cups, a stiff disc L^x is placed over each end of the tube 40 (see FIG. 6) and it will be obvious from the showing, that the compressible, semi-bulbous heads L' will always be equally spaced apart for contact purposes.

I now make reference to the standard bath tub and which is shown in vertical cross sectional view in FIG. 2, 45 parts being torn away. The tub presents the usual substantially vertical side walls M' with top outstanding rim M^x and bottom M^b and the tub as a whole being supported by corner legs, one of which is shown at P, broken away. The side walls generally curve inwardly 50 and downwardly to meet and support the tub bottom and such inwardly curving portions are indicated at M^c.

It is customary for one taking a shower bath to stand on the tub bottom and spray warm water under pressure and suitable temperature onto his body from an overhead 55 spray nozzle. As such is well known, the nozzle is not herein shown or described. It is also common practice to use an overhead suspended curtain, the lower end of which, and indicated at Q, extends downwardly into the tub and adjacent the side walls and the purpose of which 60 is to prevent spray water escaping onto the floor supporting the tub.

When one desires to take a shower bath and using my stool, the stool is inserted into the tub and initially spread to bring the friction cups into frictional contact with the 65 side walls thereof, and the weight of the stool itself primarily hold it there in suspension. Such having been done, the bather then sits down on the seat sections J and K and his added body weight highly compresses the cups into contact with the side walls and with such intensity that any slippage is prevented in any direction.

The positioning of the height of the stool within the tub can be varied, but for all practical purposes, the

position of the stool within the tub will be as shown in FIG. 2 where it will be seen that the friction cups are engaged with the tub walls at the points where the sides of the tub start to curve inwardly, and the in-curves give an added safety factor.

In using heated spray water under pressure and directed in different directions onto the body it is quite possible for the sprayed water to bulge the curtain outwardly above the rim of the tub and for such reason I have shown the lower end Q of the curtain well down within and below the rim of the tub.

It is quite common for one to take what is commonly known as a sitz bath and if one desires to do this in solid comfort, I have provided a water proof cushion R (see FIGS. 4 and 5) that can be detachably secured to the stool and rested on the seat sections J and K. It can be rendered detachable in any suitable way. I have shown it herein as a flat spring T centrally crossing the underside of the cushion and securely fastened thereto by cross straps T' sewn or otherwise fixedly fastened to the cushion. The spring has its extending ends down curved and terminating in hooks T*. To detachably secure the cushion to the stool it is only necessary to catch one of the hooks on the cross tube 14, press down, and catch the other hook on the cross tube 15 or the converse order.

Many accidents have happened in taking a standing spray bath due to the foot slipping on the bottom of the tub and such is enhanced when soap is used on the body as is quite usual, and makes the bottom of the tub slippery as well as the feet. My stool avoids any such possibility.

I want now to particularly point out that while the pairs of inner and outer legs have each been described, as a whole, as having been made from lengths of tubing interconnected by appropriate elbows, it is distinctly to be understood that the elbows could be entirely dispensed with and each pair of inner and outer legs made from a single length of tubing appropriately bent at elbow points to produce them and using a stiff metal tubing for the purpose.

To store the stool it is only necessary to spread the inner and outer legs to their contacting limits and if it be desired, the stool with the cushion secured thereto,

can be used as a seat on a floor, as it is obvious that the hooked ends of the spring will positively prevent the seat sections J and K from spreading.

What I claim is:

- 5 1. In a conventional bath tub wherein upgoing side walls of the tub have their lower portions converging inwardly and downwardly to support a horizontally disposed tub bottom, a stool inserted in the tub and presenting inner and outer pairs of well spread legs extending transversely of the tub and crossing one another and pivotally interconnected together at their points of crossing by similar pivot pins in horizontal alignment and extending centrally and lengthwise of the tub and said pairs of legs having their outermost lower ends horizontally disposed and in frictional contact with the aforesaid inwardly and downwardly inclining lower portions of the side walls, and similar, horizontally disposed, independent and spaced seat sections extending lengthwise of the tub and fixedly secured to the upper ends of the respective pairs of legs and free of the said upgoing side walls, the said pivot pins being so positioned that upon the weight of a sitter being applied on the seat sections, the outer ends of the legs at their points of contact with the inwardly and downwardly converging lower portions of the side walls aforesaid, will develop sufficient out pressure to prevent slippage of the stool under the applied weight of the sitter.
- 10 2. The device as claimed in claim 1 wherein the outer, lower ends of all legs are provided with similar compressible friction cups.
- 15 3. The device as claimed in claim 1 wherein a water-proof cushion is supplied for detachable connection to the seat sections to prevent spreading thereto, as and when desired.
